UNITED STATES PATENT OFFICE.

WILLIAM E. LEE, OF WEYMOUTH, MASSACHUSETTS.

HAND-PLANE.

SPECIFICATION forming part of Letters Patent No. 760,074, dated May 17, 1904.

Application filed February 4, 1901. Serial No. 45,815. (No model.)

To all whom it may concern:

Be it known that I, WILLIAM E. LEE, a citizen of the United States, residing at Weymouth, in the county of Norfolk and State of Massachusetts, have invented certain new and useful Improvements in Hand-Planes, of which the following is a full, clear, and exact description.

In the construction of planes for ordinary carpentry work and for smoothing floors and decks and sides of vessels it is customary to provide a smooth - sided block with a blade which by being forced over the surface of the wood cuts thin shavings therefrom until the desired exactness is obtained. The trouble with this form of plane is that considerable muscular energy is required in operating it, it is comparatively slow in action, it makes bad work on knots and cross-grained sections of the wood, and in many forms of work, as in planing floors, decks, and especially sides of vessels, it is awkward to use and very hard and tiresome. Attempts have been made to construct a deck-smoothing instrument mounted on supporting-wheels the forcible rotation of which by the propulsion of the instrument was caused to actuate revolving cutter-blades; but this has proved of even less convenience than the ordinary hand - plane, considerable more energy being required for its propulsion and it being less efficient in character of work performed.

The object of my invention is the construction of a hand-plane which should be free from all the objections above referred to and in addition embody certain positive advantages.

My invention for this purpose comprises a smooth - faced block carrying revolving cutter - blades operated by an electric motor receiving its energizing current through suitable lead-wires from an external source of electricity.

Referring to the drawings forming part of this specification, Figure 1 is a longitudinal section of my plane through the line X X in Fig. 4. Fig. 2 is a side elevation, partly in section, of a portion of the same. Fig. 3 is a detail view of a cross-bar forming part of the cutter-adjusting mechanism. Fig. 4 is a plan view, partly in section, along the line Y Y in

Fig. 1. Fig. 5 is a plan view of the rotary cutter, showing the device for setting the blades. Fig. 6 is a transverse section of said device.

The plane - block is formed, preferably, of cast-steel, and consists of the smooth bottom 1 and sides 2. The handle 6 is of the usual construction, suitably affixed to the bottom. In the bottom is a slot 3 to receive the cutter-blades 10, which are adjustably secured to the blocks 13, rigid with the shaft 14. At the left-hand end of the cutter-blades is the spur-gear 15, designed for rotating the latter. This gear meshes with the larger gear 45, fixed upon the shaft 44, carrying the armature 40, said shaft being revoluble in suitable bearing-bosses projecting from the sides 2. This armature has commutator 41 and brushes 42, supported by the insulated posts 43, the current being derived through the lead-wires 60, provided with terminal plugs 61, adapted to be inserted in suitable sockets, the latter being connected with the motor through the switch 65, which is designed to be easily operated by means of the forefinger of the hand grasping the handle 6.

The motor and gearing are protected by the non-magnetic shield 48. (Shown in Figs. 1 and 4.)

To render the cutter capable of adjustment both to insure its parallelism with the face of the plane and to vary the cut, the cutter-bearings are arranged as follows: Each end of the shaft 14 is tapered and surrounded with antifriction - balls 17, fitting in the cup 20. Said cups are externally threaded and turn friction-tight in the correspondingly-threaded sockets 21 of the levers 22. These levers are offset, as shown in Fig. 4, a part being flush with the interior of the sides and part being flush with the exterior, the sides being apertured to make room for the same and said levers being loosely mounted on the spindle 26, terminally fixed in the sides 2. The end of each lever opposite to the socket 21 is forked, as shown in Fig. 2, and into such forks or notches 25 are inserted the shouldered ends of the bar 27. This bar is introduced between the three fingers 32 34, projecting from the sleeve 30, screws 33 35 serving to locate said bar firmly in place. This is done by the screw 100

33 turning in the central finger 32 against the bar 27 and the screws 35 turning in the bar 27 against the under fingers 34.

The sleeve 30 is revolvably mounted on the 5 spindle 31, held by the plane sides 2, and has the arm 36 projecting into engagement with the screw-threads 38. This worm or member formed with said threads is rotatable on the screw shown in dotted lines as fixed in the 10 boss 4 and holding the knob 60. Said worm is moved by means of the short lever 37 and by its movement rocks the sleeve 30 and the 15 fingers projecting therefrom, and hence the levers 22, thereby raising and lowering the 20 rotating cutters. To adjust the inclination of said cutters with respect to the face of the plane, one of the screws 35 is loosened and the other tightened, thereby changing the angle of the bar relative to the face of the plane. 25 This varies the positions of the levers 22, throwing one slightly up and the other slightly down, and so shifts the angle of the cutter-shaft 14 relative the face of the plane, but in an opposite direction to the shifting of the bar 27. In this manner I am enabled to adjust the 30 angle of the cutter-blades with respect to the plane, while the lever 37 permits of a quick adjustment of the said blades to cause them to cut a thinner or thicker shaving, as desired. 35 The reference-numeral 29 indicates a guard for preventing the shavings from being thrown upon and accumulating about the knob and the adjusting devices.

The cutter-blades 10 are made adjustable 35 by means of the slots 11 and screws 12 in order to enable wear to be taken up. To properly set the blades after having been sharpened and replaced, I employ the gage 50. (Shown in Figs. 1, 5, and 6.) By bringing 40 this gage up to a horizontal position and setting the upper corners of the blocks 13 against the edge 50^a thereof the blade on the upper face of said blocks is brought against the ledge or bar proper, 50, and its accurate adjustment thereby assured. As shown in Figs. 45 5 and 6, this gage-bar is formed with two arms 52, pivoted to the shield 48, one of the arm ends being made rectangular and a leaf-spring 53 provided to press against such rectangular ends and to thereby retain the gage-bar in either its normal vertical position out of the way of the cutter-blades or raised into the position shown in Figs. 1 and 6.

As indicated in Fig. 2, the socket ends 50 of the levers 22 are split at 24 in order that the cups 20 may be held so tightly as to prevent their unloosening.

In using this electric plane the handle 6 is 60 grasped with the right hand, and the left hand is placed when needed upon the knob 60 and the plane moved at the proper speed over the board or other length of wood to be planed. If the rotating cutter-blades bite too deeply, the fingers of the left hand on the knob give 65 the lever 37 a movement toward the left,

while a thicker cut is obtained by swinging the lever toward the right. With the forefinger of the right hand the switch 65 is turned to throw the current on or off, according to whether work is being done or the 70 plane is to be laid upon the bench. In this manner the electric plane is used substantially the same as those of the present construction, its advantages being, however, very numerous and marked, both as to rapidity and accuracy 75 of work accomplished and the ease with which it can be done.

The arrangement of the cutter-adjusting lever 37 is such that whenever the work required of the cutter is too great and it slows down too much the lever can be instantly swung toward the left and the strain on the cutter reduced.

What I claim as my invention, and for which I desire Letters Patent, is as follows, to-wit: 85

1. The combination with a smooth-surfaced plane-block having a transverse slot therein, of a revolving cutter located in said slot, an electric motor actuating said cutter, and lead-wires to said motor from an external source of 90 electricity, substantially as described.

2. The combination with a smooth-surfaced plane-block, having a transverse slot therein, of a revolving cutter located in said slot, bearings for said cutter adjustable both individually and jointly, an electric motor for actuating said cutter, and lead-wires to the motor from an external source of electricity, substantially as described. 95

3. The combination with a plane-block, of a 100 revolving cutter, bearings therefor, two levers pivotally held in said block, means for angularly adjusting said levers, and a motor for actuating the cutter, substantially as described. 105

4. The combination with a plane-block, of a revolving cutter, bearings therefor, a lever for each bearing pivoted to the block, means for adjusting said levers separately and for moving them in unison, and a motor for actuating 110 the cutter, substantially as described.

5. The combination with a plane-block, of a revolving cutter, bearings therefor, two pivoted levers supporting the bearings, a cross-bar connected with said levers, pivoted fingers including said cross-bar and set-screws 115 adjustably binding said fingers to said cross-bar, and means for adjusting all said fingers in unison, substantially as described.

6. The combination with a plane-block, of a 120 revolving cutter, bearings therefor, two levers supporting said bearings, a rocking sleeve having the fingers including said cross-bar and adjustably bound thereto, an arm projecting from said sleeve, and a lever-operated cam-groove engaging said arm, substantially as described. 125

7. The combination of the plane-block comprising the bottom and two sides, said bottom having the revolving cutter located therein 130

and the sides having the slots, the offset levers partially located in said slots and formed with bearings revolubly supporting said cutter, and means for adjusting said levers, substantially 5 as described.

8. The combination of the plane-block comprising the bottom and two sides each slotted, the offset levers partially located in the side slots, the ball-bearing cups adjustably held by 10 said levers, the shaft having its ends fitted to

said ball-bearings, the cutter-blades carried by said shaft, and means for revolving said shaft, substantially as described.

In testimony that I claim the foregoing invention I have hereunto set my hand this 16th 15 day of January, 1901.

WILLIAM E. LEE.
